(57) CLAIM

The ornamental design for a headwear carrying case, as shown and described.

DESCRIPTION

FIG. 1 is a front top left side perspective view of a headwear carrying case, showing my new design;

FIG. 2 is a rear bottom right side perspective view of the headwear carrying case shown in an alternate configuration in an upside-down position;

FIG. 3 is a front elevational view of the headwear carrying case of FIG. 1;

FIG. 4 is a rear elevational view of the headwear carrying case of FIG. 1;

FIG. 5 is a left side elevational view of the headwear carrying case of FIG. 1, the right side elevational view being a mirror image;

FIG. 6 is a top plan view of the headwear carrying case of FIG. 1;

FIG. 7 is a bottom plan view of the headwear carrying case of FIG. 1; and,

FIG. 8 is top perspective view of the headwear carrying case shown in an alternate configuration in an open position. The broken lines indicate portions of the headwear carrying case that form no part of the claimed design.

1 Claim, 8 Drawing Sheets
